(57) **CLAIM**

The ornamental design for a protective corner strip for a suitcase, as shown and described.

DESCRIPTION

FIG. 1 is a perspective view of a protective corner strip for a suitcase showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof, the right side being a mirror image of that shown; and,

FIG. 7 is a perspective view of a protective corner strip in condition of use with a suitcase shown on a reduced scale. The broken line showing of a suit case is for illustrative purposes only and forms no part of the claimed design.
